J. H. HULL

BROACH HOLDER

Filed June 29, 1921

FIG. 1.

FIG. 2.

FIG. 3.

FIG. 4.

Inventor

J. H. Hull,

By *John Murphy Jr.*
Attorney

UNITED STATES PATENT OFFICE.

JOHN H. HULL, OF COLE CAMP, MISSOURI.

BROACH HOLDER.

Application filed June 29, 1921. Serial No. 481,366.

To all whom it may concern:

Be it known that I, JOHN H. HULL, a citizen of the United States, residing at Cole Camp, in the county of Benton and State 5 of Missouri, have invented certain new and useful Improvements in Broach Holders; and I do hereby declare the following to be a full, clear, and exact description of the invention, such as will enable others skilled in 10 the art to which it appertains to make and use the same.

The invention relates more particularly to dental instruments such as a holder for broaches whereby the article may be quickly 15 and easily gripped or released and when in position is held secure against possible loosening.

The instrument consists of a handle embodying two jaws and a lever for closing the 20 jaws and holding them pressed together with the broach clamped therebetween, said jaws springing apart when the lever is moved to open position thereby instantly releasing the broach by a single movement of 25 the lever.

Other objects and advantages will be apparent and suggest themselves as the nature of the invention is understood.

While the drawing illustrates an embodiment 30 of the invention it is to be understood that in adapting the same to meet different conditions and requirements, various changes in the form, proportion and minor details of construction may be resorted to without departing from the nature of the invention.

Referring to the accompanying drawing forming a part of the specification,

Figure 1 is a side view of a broach holder embodying the invention.

Figure 2 is a sectional detail thereof.

Figure 3 is a section on the line $x-x$ of Figure 1, and

Figure 4 is a section on the line $y-y$ of Figure 1.

Corresponding and like parts are referred to in the following description and designated in the several views of the drawing by like reference characters.

The device comprises a relatively slender 50 handle embodying complementary members 1 and 2 united at one end and terminating in coacting jaws 3 between which the broach or other article to be held is clamped. The gripping faces of the jaws 3 are serrated, 55 toothed or otherwise roughened to prevent

slipping and insure a firm grip on the article to be held. The jaws are longitudinally grooved to center the article and prevent lateral displacement thereof. Lateral ears 4 project from the member 1 toward and beyond the member 2 and embrace opposite sides of the latter. The member 2, as best shown in Figure 3, has a portion which is reduced in width and which fits snugly between the ears 4, thus providing a structure 60 in which the ears are positioned within the plane of the members 1 and 2. These ears prevent lateral movement of the jaws and provide supporting means for the operating lever 5. The lever 5 is pivoted between the 65 outer ends of the ears 4 and has a cam portion 6 upon its inner side adjacent the pivotal end to engage the member 2 and press the same toward the member 1 whereby to close the jaws 3 and firmly and securely grip the 70 article placed therebetween. A longitudinal groove or channel 7 is formed in the outer side of the member 2 for the reception of the major portion of the lever 5 to house the same and provide an instrument of compact 75 form and arrangement. The groove or channel 7 enables the outer portion of the lever to come flush with the outer side of the member 2 when in closed position as indicated most clearly in Figure 1. The complementary members 1 and 2 are spaced a substantially uniform distance apart throughout the major portion of their lengths, and their free ends are thickened inwardly to 80 form the jaw faces 3.

The holder is of such construction that when the lever 5 is turned to occupy a position approximately at a right angle to the handle, the jaws 3 spring apart and when the lever 5 is moved to lie in the groove or channel 7, the jaws 3 are pressed together and grip the broach or other article placed therebetween. When the jaws 3 are closed the cam portion 6 of the lever 5 is beyond the fulcrum of the lever, so that the tendency of the jaws to open reacts to maintain the lever 5 in closed position and press the outer end thereof more closely against the side of the member 2. The member 2 has a notch or cut away portion adjacent its free end in 95 which operates the cam 6. The notch and the groove 7 cooperate to permit the cam 6 to move beyond the fulcrum of the lever 5. The broach or article clamped between the jaws 3 is instantly released when the lever 5 100 105 110

is moved into open position since the jaws 3 spring apart by the spring action of the members 1 and 2.

Having thus described the invention, what

5 I claim is:—

A dental broach holder comprising a pair of complementary elongated members rigidly connected at one end and spaced a substantially uniform distance apart throughout 10 their lengths when in clamping and non-clamping positions, said members adjacent their free ends being thickened inwardly to provide opposed complementary jaw faces, each of said jaw faces being serrated and 15 provided with a longitudinally extending semi-cylindrical groove to receive a broach, a pair of ears formed on one of said members at the rear end of the jaw face thereof, one of said ears being disposed at each side of 20 said member and in the plane thereof, the other of said members having a portion reduced in width and snugly fitting between

said ears, a cam pivoted between said ears above said second member and adapted to move the complementary jaws into clamping 25 position, said last named member having a cut away portion in which the said cam operates and having a groove to receive the cam lever when the jaws are moved into clamping position, said cut away portion 30 and groove cooperating with said cam and cam lever whereby when the cam is in locking position the lever is flush with the outer surface of the member having the groove and the cam is beyond the fulcrum of the 35 lever and any tendency of the jaws to move apart and release the broach reacts to maintain the lever in closed position.

In testimony whereof I affix my signature in presence of two witnesses.

JOHN H. HULL.
